UNITED STATES PATENT OFFICE.

CHARLES E. BIRD, OF MINNEAPOLIS, MINNESOTA.

MAN-LIFT ELEVATOR.

1,079,159.

Specification of Letters Patent. Patented Nov. 18, 1913.

Application filed May 3, 1913. Serial No. 765,219.

To all whom it may concern:

Be it known that I, CHARLES E. BIRD, a citizen of the United States, residing at Minneapolis, in the county of Hennepin and State of Minnesota, have invented certain new and useful Improvements in Man-Lift Elevators; and I do hereby declare the following to be a full, clear, and exact description of the invention, such as will 10 enable others skilled in the art to which it appertains to make and use the same.

My invention relates to manually operated elevators and is particularly directed to the improvement of that type thereof, 15 generally known as man lifts. These so-called man lifts are found very serviceable in grain elevators, in mills and various other places, for lifting or lowering, usually one person at a time; and, as generally constructed, the car or moving platform has a counter-weight that will approximately 20 counter-poise the car and a person standing thereon. Inasmuch as the weight of different persons varies, it has hitherto been a common practice to provide supplemental 25 counter-weights adapted to be applied or removed, at will. Frequently, however, these man lifts are employed in places where most of the up and down travel will be performed by one person, in which case, the supplemental counter-weights need not be 30 employed.

In the accompanying drawings which illustrate the invention, like characters indicate like parts throughout the several views.

Referring to the drawings, Figure 1 is a view in front elevation, showing the man lift, some parts being broken away; Fig. 2 is a plan view of the parts shown in 40 Fig. 1; Fig. 3 is a side elevation of the car and certain devices applied thereto; Fig. 4 is a horizontal section taken on the line $x^4 x^4$ on Fig. 1; and Fig. 5 is a vertical section taken on line $x^5 x^5$ on Fig. 1.

45 The numeral 1 indicates the floor structure of a lower story and the numeral 2 indicates the ceiling or overhead structure of a top story, or top of a building.

The numeral 3 indicates a lever in the form 50 of a heavy beam which is pivoted at 4 to a suitable bearing 5 on the overhead structure 2. This lever 3, as shown, is cut out at its free portion and a large sheave or cable

wheel 6 is set into the same and pivoted thereto at 7.

55

The car, which is indicated as an entirety by the numeral 8, is guided by the parallel vertically extended portions of a guide cable 9, the lower ends of which are anchored to the floor 1, and the upper portion of 60 which is passed over a pair of alined guide sheaves 10 journaled to hangers 11 rigidly secured at their upper ends to the overhead structure 2. At its free end, the lever 3 is provided with a bearing foot or lug 12 that 65 rests on the transverse intermediate portion of the car guiding cable 9 and engages the same between the sheaves 10, thereby normally depressing that portion of said cable to take up the slack to keep the vertical 70 portions of said cable perfectly straight.

The car 8 is suspended from one end of a cable 13, which cable is passed over the wheel 6 and is provided at its other depending end with a weight 14. This weight 14, 75 as already indicated, will usually be heavy enough to overweight the car 8 and approximately counterbalance the weight of the car and person standing on the car.

The cable 13 is attached to the short arm 80 15 of a rock shaft 16 that is journaled in suitable bearings on the sides of the car 8, and is provided at its ends with short arms 18 having eyes or perforations through which the vertical portions of the guide 85 cable 9 are passed. The arm 15 projects at one side and the arms 18 at the opposite sides of the rock shaft 16, and normally, the weight of the car pulling in one direction and the weight 14 pulling in the other 90 direction, holds the arms 18 against stops 19 on the car 8 (see Fig. 5) and holds the said arms 18 at a right angle to the coöperating cables 9 so that the said arms move freely on the said cables, and then serve simply as 95 guides causing the car to follow the said cables. The rock shaft 16 is provided with another arm 17 which projects in a direction opposite from the short arm 15, and this arm 17 is connected by a coiled spring 20 to the 100 top cross portion of the said car. This spring 20 exerts a force which, if the cable 13 should break, would cause the arms 18 to move upward and their eyes to take a kinking bite or grip on the cable 9. Once 105 the arms 18 are caused to take a bite on

the cables 9, the weight of the car would be rendered effective to increase this bite so that the said levers then act as safety clutches to grip the vertical portions of the cable 9 and to prevent further descent of the car. The lower portion or platform end of the car 8 is, as shown, provided at its side with vertically perforated guide lugs 21 that move freely on the vertical portions 10 of the cable 9.

In providing a suitable brake device, a metal rock shaft 22 beneath the floor of the car 8 is provided with an upwardly extended foot piece or lever 23. Loosely engaging the vertical portions of the cable 9, between the upper and lower guide lugs 21 are spring set brake shoes 24 connected by links 25 to short arms 26 on the ends of the rock shaft 22. The brakes are adapted to 20 be released by stepping on the foot piece 23 and thereby disengaging the brake shoes 24 from the vertical portions of the cable 9. This form of brake is in common use and 25 well understood. An operating cable 27 is passed vertically through the platform of the car 8, and at its upper end is anchored to the overhead work 2, and at its lower end is anchored to the floor structure 1.

With the construction above described, it 30 is evident that the weight of the load of the car and the weight 14, acting through the lever 3 and cable wheel 6, automatically take up the slack of the guide cable 9 and prevent any stretching thereof, so that readjustments of the guide cable from time to time 35 is not required. As already indicated, breaking of the supporting cable 13 will cause the automatic brake device, to-wit, the rock shaft 16 and arms 18, to lock the car to the vertical portions of the guide cable and 40 thus prevent accident. Here, it is important to note that when a car descending, is locked to the vertical portions of the guide cable 9, as above stated, the sudden strain upon the 45 said cables will find considerable relief from the initial impact, by a starting of the transverse upper portion thereof. When the cable 13 is broken, only the weight of the lever 3 and wheel 6 will be effective on the 50 transverse upper portion of the cable 9. The lever 3 and wheel 6 will yield and move slightly upward and thereby afford a cushion, relieving the guide cable 9 from strains, whenever the car is descending and the 55 brake shoes 24 are suddenly thrown into action with considerable force. In man lifts or manually operated elevators of this character, it is well known that the car with a person therein may be very easily and quite 60 rapidly moved either upward or downward by the operator on the car pulling upward or downward on the anchored operating cable 27.

What I claim is:

1. The combination with overhead cable 65 guides, of a guide cable extended across said cable guides and having vertical portions anchored at their lower ends, of a car guided by the vertical portions of said cable, a counter-weighted car supporting 70 cable, and a bearing for said supporting cable exerting a downward pressure on the transverse upper portion of said guide cable.

2. The combination with overhead cable 75 guides, of a guide cable extended across said cable guides and having vertical portions anchored at their lower ends, of a car guided by the vertical portions of said cable, a counter-weighted car supporting cable, a 80 bearing for said supporting cable exerting a downward pressure on the transverse upper portion of said guide cable, and safety clutches normally held inactive by the weight of the car and its counter-weight, but 85 operative, when released by breaking of the car supporting cable, to anchor said car to said guide cable.

3. The combination with overhead cable 90 guides, of a guide cable extended across said cable guides and having vertical portions anchored at their lower ends, of a lever pivoted to an overhead support and having a bearing on the transverse upper portion of said guide cable, for automatically taking 95 up the slack thereof, a cable wheel journaled to said lever, a car guided by the vertical portions of said cable guide, and a counter-weighted cable passed over said cable wheel and supporting said car.

4. The combination with overhead cable 100 guides, of a guide cable extended across said cable guides and having vertical portions anchored at their lower ends, of a lever pivoted to an overhead support and having a 105 bearing on the transverse upper portion of said guide cable, for automatically taking up the slack thereof, a cable wheel journaled to said lever, a car guided by the vertical portions of said cable guide, a counter-weighted cable passed over said cable wheel and supporting said car, a rock shaft having 110 cable engaging safety clutches, the said cable being eccentrically attached to said rock shaft and normally exerting a force 115 holding the clutches thereof for free movements on said guide cable, and means operative when the said counter-weighted cable is broken, to cause the safety clutches of said rock shaft to grip the vertical portions of 120 said guide cable.

5. The combination with vertical guide 125 cables and a car mounted for vertical movements thereon, of a rock shaft mounted on said car and having perforated offset arms at its ends serving as safety clutches to en-

gage said guide cables, said rock shaft having at its intermediate portion oppositely projecting arms, a spring attached to one of said arms and to said car and tending to cause the clutches of said rock shaft to grip said guide cables, and a counter-weighted cable attached to the other of said arms and acting in opposition to said spring to normally hold the clutches of said rock shaft

free for sliding movements on said guide cables.

In testimony whereof I affix my signature in presence of two witnesses.

CHARLES E. BIRD.
